United States Patent Office

Des. 197,964
Patented Apr. 14, 1964

197,964

TRACTOR

Nolan Rhoades, Beloit, Wis., assignor to Simplicity Manufacturing Company, Port Washington, Wis., a corporation of Wisconsin

Filed May 29, 1963, Ser. No. 75,115

Term of patent 14 years

(Cl. D14—3)

The dominant features of my design reside in those portions thereof shown in full lines.

I claim:

The ornamental design for a tractor, as shown and described.
